UNITED STATES PATENT OFFICE.

JASPER D. PATRICK, OF MONTGOMERY, ALABAMA, ASSIGNOR OF ONE-THIRD TO
ALEXANDER FREDERICK WHITING, OF MONTGOMERY, ALABAMA.

MECHANISM FOR AUTOMATICALLY OPERATING STEAM-INJECTORS.

1,105,373.

Specification of Letters Patent.

Patented July 28, 1914.

Application filed April 20, 1914. Serial No. 833,158.

To all whom it may concern:

Be it known that I, JASPER D. PATRICK, a citizen of the United States, residing at Montgomery, in the county of Montgomery and State of Alabama, have invented certain new and useful Improvements in Mechanism for Automatically Operating Steam-Injectors, of which the following is a specification.

10 It is the primary object of this invention to provide mechanism which will render steam injectors automatically operative to as complete a degree as they are operated manually. To do this, it is not only necessary that automatic means be provided to take care of the normal or ordinary operations, but that means be also provided to perform automatically certain emergency operations. Apparatus which operates an 20 injector and does not take care of certain emergencies which are likely to arise at any time is ineffective from a practical standpoint because it has to be supplemented by manual operation and therefore in many 25 cases might as well not be provided.

My invention, as here shown, is automatic in the true sense in that it requires no supplemental manual operation, and therefore need not be watched. In other words, when 30 the injector is once set, it is thoroughly capable of taking care of itself.

My invention, however, embodies certain novel mechanism for operating injectors irrespective of emergency operations.

35 My invention furthermore provides mechanism which is universal in character in that it may be readily applied to any of the well known injectors.

In order to more fully describe my said 40 invention, reference will be had to the accompanying drawings in which,

Figure 1, illustrates partly in section and in elevation one specific embodiment of my said invention, as applied to a "Monitor" 45 steam injector, and Fig. 2, is a fragmentary detail section, on a larger scale than Fig. 1, showing the connection from the priming by-pass to the jet tube.

In carrying out my invention in the form 50 shown, I provide, among other parts, a float chamber comprising a cylindrical tank 1 attached to the boiler 2 by pipes 3 and 4, which pipes are provided respectively with hand operated cut off valves 5 and 6. Pipes 55 3 and 4 afford a communication from

the boiler to the interior of the float tank 1, opening into said tank near its top and bottom as shown. Steam is supplied to the tank 1 from the boiler through pipe 3, and water through pipe 4, thus maintaining the 60 same pressure and water level in the tank as in the boiler.

Located in tank 1 is a float 7, consisting preferably of a thin hollow copper sphere slightly less in diameter than the inner diameter of tank 1. Adjustably attached to this float as, for example, by being screwed thereto, is a stem 8 which passes upward through and makes a sliding fit with an opening in a cap 9, adapted to screw on and off the upper end of the tank and to act as a closure therefor. The opening in cap 9 through which stem 8 passes is provided with a packing nut 10 to prevent the escape of steam from the float tank 1. At the bottom of the float tank is a drain cock 11 for drawing water from the tank. Float stem 8 is connected at its upper end to a lever 12 fulcrumed as at 13 in any desired way on the boiler. Lever 12 connects on the opposite side of its fulcrum from its float stem, with two rods 14 and 15. Rod 14 is connected at its lower end to the operating arm 16 of a valve 17 connected in a steam supply pipe 18, leading from the boiler to a primer cylinder 19. In this cylinder is a piston 20 which is adapted to be moved by steam from pipe 18 against the compression of a spring 21, as hereinafter more particularly described. Piston 20 is provided with a piston rod 22, which connects with the operating arm 23 of a priming valve 24 connected in a by-pass steam pipe 25. The function of this by-pass pipe is to convey steam from the main steam feed pipe 26 to the jet tube 27 95 of the injector 28, for the purpose of priming it, the valve 25 in the present case supplanting the hand operated priming valve.

The particular form of injector shown is a "Monitor" injector, a well known form 100 of a steam injector, the construction of which need not here be described in detail.

In the construction shown, the hand operated priming valve together with the jet valve bonnet and nut are removed, and a nut 105 29 carrying a nozzle 30 is screwed into the opening in the injector casing in the place of said bonnet and nut, the nozzle 30 being provided with a beveled head 31 adapted to fit the priming valve seat 32 against which 110

it is screwed, thereby making a steam tight passage from the by-pass pipe 25 to the jet tube 27. (See Fig. 2.)

- Rod 15 is operatively connected to an arm 33 of a valve 34, connected in a steam supply pipe 35, leading from the boiler to a cylinder 36, in which cylinder is located a piston 37 operative by steam from pipe 35 against the compression of a spring 38.
- 10 Piston 37 is provided with a piston rod 39, which is flexibly connected to the operating arm 40 of a valve 41, connected in the main steam feed pipe 26, leading from the boiler to the injector. The steam from cylinder 19 is exhausted through a pipe 42, in which is connected a valve 43. This valve is operated automatically from piston rod 39, and for this purpose there may be provided any suitable operative connection between said valve and piston rod, comprising, in the case shown, a bell crank lever 44, one of the arms of which extends between two pins 45 on said piston rod, while the other arm is flexibly connected through link 25 46 to the operating arm 47 of valve 43.

The cylinder 36 is provided with two exhausts, one for the normal operation of the injector, and the other for emergency purposes. The normal exhaust from cylinder 30 36 takes place through a pipe 48, and is controlled by a valve 49 connected in said pipe. This valve 49 is operated from the float, and for this purpose is operatively connected through arm 50 to the rod 15.

35 Before taking up any of the emergency mechanism, I shall first describe briefly the normal operation of the apparatus.

In the drawing the various parts are shown in the positions which they occupy 40 when the injector is not in operation.

The main steam feed valve or "steam ram" of the injector, manually operated by handle 51, is left open and the water valve or lazy cock, manually operated by handle 45 52, is set to the desired point and left open, and the steam heater cock 53 is also left open. As the water in the boiler diminishes, float 7 will descend, and in doing so rotates lever 12 on its fulcrum, which in turn pulls rods 14 and 15 upward, causing them to operate valves 17 and 34 in a direction to open them. These valves are so timed that when the water in the boiler reaches the lower gage level, valve 17 will open and admit 55 steam to the cylinder 19. The steam in this cylinder forces piston 20 against the compression of spring 21, thus operating through piston rod 22 the arm 23 of the valve 24 in such a direction as to open the 60 same to prime the injector. At the proper time after the priming operation has commenced, valve 34 will open, admitting steam to cylinder 36, which forces its piston against the compression of spring 38. Said 65 piston in this moving operates through its

piston rod connection to open the main steam feed valve 41, thus admitting the full force of the steam from the feed pipe to the injector. When this takes place, the priming operation is automatically stopped by the opening of exhaust valve 43 of cylinder 19 through its operative connection with piston rod 39. The steam in cylinder 19 will, therefore, exhaust through pipe 42, releasing the pressure against spring 21, which then forces piston 20 down, thereby operating primer valve handle 23 to close the priming valve. The injector now operates to deliver water through its delivery outlet 54 to the boiler from the feed pipe 55 which, in the case of a locomotive, leads from the tender. As the water rises in the boiler, float 7 will rise, and by the time it reaches the second gage level, valves 17 and 34 will have both closed. Rod 15, in moving downward to close valve 34, opens exhaust valve 49, thus permitting steam to exhaust from cylinder 36. When this takes place, spring 38, acting through piston 37 and piston rod 39, will close steam supply valve 41 and stop the operation of the injector. Valves 34 and 49 are so set with respect to each other, that when one opens the other closes, and vice versa.

The timing of valves 17 and 34 is a very simple matter. It is known or determined about how long it takes a given injector to prime, and these valves are set accordingly, so that valve 34 is opened at the proper time after the valve 17 has opened.

The foregoing is the normal operation of the injector.

Reference will now be had more particularly to the parts which are designed to perform certain emergency operations.

As hereinbefore stated, the cylinder 36 is provided, in addition to its regular exhaust with an emergency exhaust. This emergency exhaust takes place through a pipe 55, in which is connected a valve 56, having an arm 57 operatively connected to an arm of a lever 58, fulcrumed in any desired way as at 59. The power arm of this lever is operatively connected through a stem 60 to a baffle plate 61 located directly under the outlet of the overflow 62 of the injector. Baffle plate 61 is movable downward against the compression of a spring 63, inserted between said plate and a fixed bracket or spider 64 made fast to the interior of a cylinder 65, which is in turn fast to the overflow nozzle 62. Cylinder 65 is provided at its bottom with an outlet 66 through which steam and water from the overflow nozzle may pass. Lever 58 extends through a slot 67 in the side of cylinder 65, and is vertically movable therein.

In the water feed pipe 55 is placed a check valve 68, opening toward the injector, and closing toward the water supply, to prevent

steam from blowing back into the water supply tank and coöperating, as hereinafter described, with the foregoing mechanism to automatically cut off the steam supplied to the injector.

For the purpose of describing the action of the emergency apparatus, we will first assume a case where the priming valve has opened, and the steam supply valve 41 has also opened, but from some cause the injector does not prime properly and fails to deliver water through its delivery nozzle to the boiler. Ordinarily in priming, steam and water will pass from the overflow nozzle 62, but not with sufficient pressure against baffle plate 61 to overcome the action of spring 63. If, however, the steam supply valve 41 is opened wide, and the injector does not deliver water through its delivery nozzle 54, steam will pass with considerable force through the overflow nozzle 62, striking baffle plate 61 and forcing it down against the compression of spring 63. The effect of this will be to rotate lever 58 in such direction as to open emergency exhaust valve 56, thus allowing steam to exhaust from cylinder 36, when spring 38 will force piston 37 in such direction as to close valve 41 and thus shut off the steam from the injector, and stop its operation. Piston rod 39 in thus closing valve 41 will also operate through bell crank lever 44 to close exhaust valve 43 of the priming cylinder and as steam is at this time flowing into the priming cylinder through pipe 18, the piston of the priming cylinder will be forced upward, thus opening priming valve 24, and which causes the injector to again prime. If this priming fails to operate correctly, the steam supply valve 41 is again closed automatically, and the priming apparatus is again brought into operation, and these operations are repeated over and over until the injector primes properly, if this is possible of accomplishment or, in other words, unless there is something so radically wrong with the injector itself that it would not prime properly even if operated manually. It also sometimes happens, from one cause or another, that steam will blow back into the water supply tank through a supply pipe 55. This happens more frequently on some injectors than others, and is not mentioned here as a special characteristic of the Monitor injector, but it will sometimes happen even with this injector. The proper thing to do in a case like this, and what would be done by one in operating an injector manually, is to cut off the steam supply to the injector, and start it over again. I accomplish this by placing in the water feed pipe the check valve 68, which will stop the flow of steam into the water supply tank and divert it through the overflow nozzle, causing the said steam, issuing from said nozzle

to operate upon the baffle plate 61 to automatically stop the operation of the injector, as above described.

It will be seen from the foregoing description that I have provided a mechanism for the operation of a steam injector which is, in the true sense of the word, automatic. Not only does this apparatus perform operations automatically, which would be performed manually in operating an injector, but it performs them in a similar way. For example, to obtain the best results, or, in other words, to be sure that an injector will operate when its valves are opened, these valves should not be opened with a jerk or too quickly. This is taken care of in my apparatus by cushioning the pistons 20 and 37 on both sides. When they are moved by the steam, they move against cushions afforded by the springs 21 and 38, and when they are moved by the springs, they are moved against cushions afforded by the steam on the other side of the pistons. The pistons thus move in each direction moderately so as not only to insure certain operation of the injector, but also to save wear and tear on the mechanism.

The various valves 17, 34, 24, 41, 43, 49 and 56 may be plug valves, or of any other suitable construction which will perform the desired function.

The stiffness of springs 21 and 38 will vary according to the particular steam pressure at which the injector must work.

The cylinders 19 and 36, and the various operating levers 12, 44 and 58 are preferably, in the case of a locomotive, mounted upon the boiler, but I do not limit my invention to any particular way of supporting the parts.

While I have herein shown and described one specific embodiment of my invention, various modifications thereof may be made without departing from the true spirit thereof. Also, while I have here shown my invention as applied to a "Monitor" injector, it is applicable as well to many other forms of injectors or inspirators.

The Monitor injector is shown principally for the reason that it is one of the most difficult injectors to operate automatically. Some injectors, for example, have no priming valve. In applying my invention to the latter kind of injector, obviously it is not necessary to provide means for operating a priming valve, in which case the priming parts of my apparatus may be omitted.

What I claim is:

1. The combination with a steam injector, of automatic means to prime said injector, automatic means to control the steam feed of said injector, and means operated by the said steam feed controlling means to automatically stop the operation of said priming means.

2. The combination with a steam injector having a priming valve and a valve to control the steam feed to the injector, of automatic means to operate said priming valve, and automatic means timed to operate at a definite period after the opening of said priming valve to operate said steam feed valve. 70
3. The combination with a steam injector having a steam feed valve, of automatic means to operate said valve, and means operable automatically to close said valve upon the failure of the injector to operate after the said valve is opened by the first mentioned automatic means. 75
4. The combination with a steam injector having a steam feed valve, of float controlled automatic means to operate said valve, and emergency means operable automatically independently of said float controlling means, to close said valve upon the failure of the injector to operate upon the opening of said valve by the float controlled mechanism. 80
5. The combination with a steam injector having a steam feed valve and an overflow outlet, a float controlled mechanism for automatically operating said feed valve, and mechanism operable from the overflow outlet of said injector to cause said float controlled mechanism to automatically close said feed valve. 90
6. The combination with a steam injector having a steam feed valve and overflow outlet, of a baffle connected to said injector for operation by the flow of fluid from said overflow outlet, a valve connected to said baffle for operation thereby, a cylinder having an emergency exhaust controlled by said valve and a piston operatively connected to said steam feed valve, means to deliver steam to said cylinder, a valve controlling said delivery, and float operative means controlling the last named valve. 95
7. The combination with a steam injector having a steam feed valve, of float controlled automatic means to operate said valve, and emergency means operable upon the failure of the injector to work after its steam feed valve is opened, and independently of said float mechanism to close said steam feed valve and cause said float operated mechanism to again open said steam feed valve. 100
8. The combination with a steam injector, of automatic means to control the steam supply thereto, said means comprising a cylinder, a piston adapted to reciprocate in said cylinder, a spring against which said piston is adapted to move in one direction, said cylinder having a steam inlet, a normal exhaust and emergency exhaust, valves controlling said steam inlet and exhausts, float operated means controlling the valves of the steam inlet and normal exhaust, and means operative automatically independ- 110
- ently of the float mechanism to operate the emergency exhaust. 115
9. The combination with a steam injector and boiler, of automatic means to control the steam feed to the injector, said means comprising a cylinder, a piston reciprocable in said piston, a spring against which said piston is movable in one direction, a steam inlet opening into said cylinder on one side of said piston, an exhaust opening from said cylinder on the same side of said piston, a valve controlling said steam inlet and a valve controlling said exhaust, a float tank opening to said boiler, a float in said tank, a lever connected to said float and operative connection between said lever and said valves, and means operative from the overflow of said injector to automatically cut off the supply of steam to said injector. 120
10. The combination with a steam injector and boiler, of automatic means to control the steam feed to the injector, said means comprising a cylinder, a piston reciprocable in said piston, a spring against which said piston is movable in one direction, a steam inlet opening into said cylinder on one side of said piston, an exhaust opening from said cylinder on the same side of said piston, a valve controlling said steam inlet and a valve controlling said exhaust, a float tank opening to said boiler, a float in said tank, a lever connected to said float, and operative connection between said lever and said valves. 125
11. The combination with a steam injector connected to a source of steam supply and to a source of water supply and having an overflow outlet, of float controlled automatic means to control the steam supply to said injector, a check valve located in the connection from the injector to the water supply, and means operative from the overflow outlet, to automatically cut off the supply of steam to said injector. 130
12. The combination with a steam injector having a steam feed pipe connected thereto, of a valve located in said steam feed pipe and controlling the delivery of steam to said injector, a by-pass around said steam feed valve for conveying steam to said injector to prime the same, a priming valve in said by-pass, float controlled mechanism connected to said by-pass valve to operate the same, float controlled mechanism connected to said steam feed valve to operate the same, and mechanism operated by the feed valve operating mechanism to cause the float controlled priming valve operating mechanism to close said by-pass valve to stop the priming operation. 135
13. The combination with a steam injector having a priming valve, a steam feed valve, and an overflow outlet, of a cylinder having a piston and admission and exhaust openings on one side of said piston, a spring

against which said piston is movable, operative connection between said piston and priming valve, a valve for controlling the admission of steam to said cylinder, and a 5 valve for controlling the exhaust of steam therefrom, a second cylinder having a piston and admission and exhaust openings on one side of said piston, a spring against which said piston is movable, operative connection 10 between the piston of the last named cylinder and said steam feed valve, operative connection to control the exhaust valve of the priming valve operating cylinder from the piston of the feed valve operating cylinder, 15 float operated means to control the operation of the steam admission valve of the priming

cylinder and the admission valve and exhaust valve of the steam feed valve operating cylinder, an emergency exhaust for said last named cylinder, a valve controlling 20 said exhaust, and mechanism operable by the emission of fluid from the overflow outlet of said injector to operate said emergency exhaust valve to open the emergency exhaust. 25

In testimony whereof I affix my signature in presence of two witnesses.
